UNITED STATES PATENT OFFICE

MORGAN J. HAMMERS, OF STAMFORD, CONNECTICUT, ASSIGNOR TO PETROLEUM HEAT AND POWER COMPANY, OF NEW YORK, N. Y., A CORPORATION OF DELAWARE

OIL BURNING APPARATUS

Application filed November 4, 1930. Serial No. 493,262.

This invention relates to an improvement in oil burning apparatus, and has for one of its objects the provision of a construction which is exceedingly efficient in operation, the boiler or heat absorbing medium employed being of such new and novel construction and so disposed with relation to the burner as to insure maximum efficiency in operation.

10 A further object of the invention is the provision of a construction in which the burner and boiler may be said to constitute a unitary structure, thereby enabling a manufacturer to supply a complete heating equipment with the assurance that the same will function properly.

15 A still further object of the invention is to provide a completely enclosed structure, the heat absorbing medium and the burner being enclosed in an insulated casing, the casing and the heat absorbing medium being so constructed and so disposed with reference to the burner that the hot gases resulting from the combustion of fuel in the fire chamber 25 will be confined and directed against the heat absorbing medium.

20 A still further object of the present invention is the provision of a construction in which the heat absorbing medium and the burner are so disposed relatively that while constituting or providing a unitary structure the burner is readily removable for inspection and repair.

25 A still further object of the invention is the provision of a construction employing a plurality of water circulating supporting tubes intermediate the water jacket of the combustion chamber and a steam or hot water chamber above the combustion chamber, in conjunction with a water circulating sheet in the water jacket, thereby promoting very rapidly an unobstructed water circulation.

30 A still further object of the invention is the provision of a construction embodying coiled heat absorbing members intermediate the water jacket and the chamber at the top of the structure, these members being of copper or other material providing for very rapid heat transfer, and so disposed with reference to the burner that hot water or steam is gen-

erated almost instantaneously. The present invention provides also for the removal of these members independently of each other.

The present invention provides also for the upwardly moving gases of combustion to contact with all heat absorbing surfaces in their path with a minimum restriction. This permits operation with a very limited draft and hence installation in buildings where the draft may be inadequate for the ordinary 40 type of oil burner.

The present invention also provides a construction in which due to the rapid circulation of the water and the practically instantaneous generation of steam or hot water, 45 the formation of scale in the principal heat absorbing portions of the boiler is prevented to a very large extent.

As already pointed out, the present invention provides an enclosed structure, and in 50 this connection it is to be noted that the casing constituting the enclosure is very easily removable in the event it is desired to clean the inside of the boiler.

In the drawings accompanying this application:

55 Figs. 1 and 2 are side and front elevational views of an embodiment of the present invention;

Fig. 3 is a vertical section through the 60 apparatus shown in Fig. 1;

Fig. 4 is a similar section taken through the apparatus as shown in Fig. 2;

Fig. 5 is a section on the line 5—5 of Fig. 3;

Fig. 6 is a section on the line 6—6 of Fig. 3; 65 and

Fig. 7 a section on the line 7—7 of Fig. 3.

Referring to the drawings in detail: The heat absorbing medium has been illustrated in the form of a boiler of novel construction and comprising a steam or hot water chamber designated 1 at the upper part thereof, a water circulating chamber or water jacket 2 at the bottom of the structure, and intermediate heat exchange coils 3. As will be seen from Figs. 5 and 7, for instance, the chambers 1 and 2 are roughly circular in plan, while the heat exchange coils 3 are arranged in a circle in spaced relation. These coils are of copper or some other suitable material in

which heat transfer is practically instantaneous.

5 The coils are connected top and bottom to the steam or hot water chamber chest 1 and water jacket 2 by unions 4 and 5. By simply disconnecting the proper unions it will at once be apparent that any coil may be removed for repair or replacement independently of the other coils.

10 In addition to the foregoing the present apparatus provides a plurality of water circulating and supporting tubes designated 6 and likewise arranged roughly in a circle. Four of these tubes have been shown by way 15 of illustration, and it is to be noted that they are so placed with reference to the coils 3 as not to interfere with the independent removability of these coils already referred to.

The steam or hot water chest or chamber 1 20 is provided with flues 7.

The water jacket 2 as will be seen from Fig. 4, for example, surrounds the combustion chamber designated 8 and into which projects the burner 9 as will be pointed out 25 hereinafter. Within this jacket and spaced from the walls thereof is a water circulating sheet 10, provided with large notches or cut-outs 11 and 12 in its upper and lower edges, respectively. This water circulating sheet it 30 will be appreciated promotes circulation of the water in the jacket, and taken in conjunction with the tubes 6 and coils 3 insures rapid circulation of all the water in the system. As a result the formation of scale in the principal heat absorbing portions of the boiler is 35 reduced to a minimum.

Beneath the water jacket 2 is a plate 13 on 40 which rests the structure of the water jacket, this plate being cut out at the center as shown to permit of the insertion of the burner 9 therethrough into the combustion chamber. It may be noted at this point that the wall of 45 the combustion chamber about the burner is lined with fire brick or some other such suitable material, shown at 14.

50 Bolted to the underside of the supporting plate 13 is a burner supporting plate 15, the burner being suspended from this plate. The burner is of the vertical type and comprises a vertically mounted driving motor 16, on the armature shaft 17 of which is mounted a rotary atomizing cup 18, the cup as will be appreciated rotating about a vertical axis. Surrounding the cup 18 is an air deflecting 55 ring 19, while 20 indicates a fan housing within which is mounted a fan (not shown) and which supplies air to the interior of the cup 18 as well as to the area immediately surrounding the exterior of the cup. Oil is supplied to the cup through pipe or conduit 21. This burner structure is all described and claimed in detail in a co-pending application 60 Serial No. 493,263 filed November 4, 1930 so will not be referred to herein in further detail.

From the description thus far given it will be seen that the present construction is such as to insure the maximum in efficiency of operation, the chamber 1 and jacket 2 as well as the coils 3 and tubes 6 being so arranged as to provide free circulation of the water in the system, while the disposition of these parts with respect to the combustion chamber is such that the hot gases of combustion will wipe all the heat absorbing surfaces with the minimum of restriction.

70 The entire apparatus is so constructed that the same may be enclosed as a unit in an insulated casing and shipped in that condition. The casing which is designated 22 is heat insulated and on the outside is covered with metal. The sides and the top of the casing are independently removable. The door 23 is removable with the front plate of the casing. This is of great convenience in that it permits of access to the interior of the apparatus without disassembling the whole unit. For example, the front plate of the casing may be removed independently of the sides and this permits of access to the whole front 80 of the interior mechanism. The lower part of the casing of the apparatus is not necessarily heat absorbing and comprises front plate and side members designated 25. These can be removed independently so that 85 access may be had to the burner. For instance, it might be necessary or desirable to remove the burner for purposes of repair or inspection, in which case it is only necessary to remove the front plate of the lower part 90 of the casing structure whereupon access may be had to the bolts by which the burner is held in place together with the various other connections such as the oil connection, for example, so that the burner may be taken out 95 bodily.

100 The automatic controls for the equipment may all be placed on the outside of the casing of the apparatus so as to be accessible at all times.

110 For convenience in handling the casing is provided with a plurality of holes 26 normally plugged with plugs 27. These plugs can be removed and eye bolts substituted through which bars may be slipped to permit of the whole apparatus being lifted or raised.

115 What is claimed is:—

120 1. In apparatus of the class described, the combination of an open top water jacketed combustion chamber, a fluid chamber disposed above the combustion chamber, heat exchange coils intermediate the water jacket of the combustion chamber and the fluid chamber, said coils being so disposed relatively to each other and to the combustion chamber as to provide a flue structure for the passage of hot gases from the combustion chamber along and in contact with said heat exchange coils to said heat absorbing medium, water circulating tubes intermediate the

water jacket and said fluid chamber and communicating with said jacket and chamber; and a water circulating sheet in said water jacket, said sheet being provided with upper and lower openings, said tubes and coils being so connected to said water jacket that water entering the same from the said tubes passes through the lower set of openings in the said circulating sheet upwardly along 10 said sheet and outwardly through the upper set of openings to reach the said coils.

2. In apparatus of the class described, the combination of a water jacketed combustion chamber, a fluid chamber above said combustion chamber and directly in the path of hot gases rising therefrom, intermediate heat exchange coils communicating with the water jacket and with said fluid chamber and arranged to provide a flue structure for the passage of combustion gases to the fluid chamber, water circulating tubes intermediate the water jacket and said fluid chamber and communicating with said jacket and chamber and a water circulating sheet in said jacket, said sheet being provided with upper and lower openings and said tubes and coils being so connected to said water jacket that water entering the same from the said tubes passes through the lower set of openings in the 25 said circulating sheet upwardly along said sheet and outwardly through the upper set of openings to reach the said coils.

3. In apparatus of the class described, the combination of a water jacketed open top combustion chamber, a fluid chamber above the combustion chamber and directly in the path of hot gases rising from the combustion chamber, a plurality of helically wound heat exchange coils intermediate the water jacket and the combustion chamber and the said fluid chamber and communicating therewith, said coils being so disposed relatively to each other and to the combustion chamber as to provide a flue structure for the passage of 40 hot gases to the fluid chamber, the tubes themselves due to their helical formation acting as individual flues, and a plurality of flues in said fluid chamber in line with said coils.

4. In apparatus of the class described, the combination of a water jacketed open top combustion chamber, a fluid chamber above the combustion chamber and directly in the path of hot gases rising from the combustion chamber, a plurality of helically wound heat exchange coils intermediate the water jacket of the combustion chamber, said fluid chamber and detachable connections for attaching the coils to said fluid chamber and water jacket independently of each other, said coils being so disposed relatively to each other and to the combustion chamber as to provide a flue structure for the passage of hot gases to the fluid chamber, the tubes themselves due to their helical formation act-

ing as individual flues, and flues in said fluid chamber in line with said coils.

5. In apparatus of the class described, the combination of a water jacketed open top combustion chamber, a fluid chamber above 70 the combustion chamber and directly in the path of hot gases rising from the combustion chamber, a plurality of helically wound heat exchange coils intermediate the water jacket and the combustion chamber and the said fluid chamber and in communication therewith, said coils being so disposed relatively to each other and to the combustion chamber as to provide a flue structure for the passage of hot gases to the fluid chamber, the tubes 80 themselves due to their helical formation acting as individual flues, a plurality of flues in said fluid chamber in line with said coils, and a burner at the bottom of the combustion chamber. 85

This specification signed this 3rd day of November, 1930.
